US00D818743S

(12) **United States Design Patent** (10) **Patent No.:** **US D818,743 S**
Zanki et al. (45) **Date of Patent:** **** May 29, 2018**

(54) **SUPPORT APPARATUS**

- (71) Applicants: **Logan Zanki**, North Plainfield, NJ (US); **Kathleen Zanki**, North Plainfield, NJ (US)
- (72) Inventors: **Logan Zanki**, North Plainfield, NJ (US); **Kathleen Zanki**, North Plainfield, NJ (US)

(***) Term: **15 Years**(21) Appl. No.: **29/624,362**(22) Filed: **Oct. 31, 2017****Related U.S. Application Data**

(62) Division of application No. 29/555,110, filed on Feb. 18, 2016, now Pat. No. Des. 805,812.

(51) **LOC (11) Cl.** **06-09**(52) **U.S. Cl.**USPC ..... **D6/601**(58) **Field of Classification Search**

USPC D6/333, 349, 355, 375, 388, 512, 563, D6/564, 595, 596, 601, 604, 611, 707, D6/715, 716, 716.1; D24/183–185, 234; D21/803, 804, 805, 809; 5/401, 420, 5/600, 630, 631, 632, 633, 635, 636, 638, 5/639, 646, 652, 652.1, 655, 703, 730; 297/1, 2, 4, 93, 180.11, 195.1, 195.11, 297/195.13, 393, 397, 452.12, 452.14, 297/452.15, 452.21, 452.24, 452.26, 297/452.48, 452.62, 482

Primary Examiner — Michelle E Wilson*Assistant Examiner* — Sanjeev Paul(74) *Attorney, Agent, or Firm* — Gearhart Law LLC(57) **CLAIM**

The ornamental design for a support apparatus, as shown and described.

DESCRIPTION

FIG. 1 is a perspective view of a support apparatus.

FIG. 2 is a back view thereof.

FIG. 3 is a front view thereof.

FIG. 4 is a right side view thereof.

FIG. 5 is a left side view thereof.

FIG. 6 is a top view of thereof; and,

FIG. 7 is a bottom view thereof.
